CLAIM

The ornamental design for an insect trap tray, as shown and described.

DESCRIPTION

FIG. 1 is a top front perspective view of the insect trap tray;

FIG. 2 is a front elevation view thereof;

FIG. 3 is a rear elevation view thereof;

FIG. 4 is a right elevation view thereof;

FIG. 5 is a left elevation view thereof;

FIG. 6 is a top view thereof; and,

FIG. 7 is a bottom view thereof.

The insect trap tray is adapted to be placed in a compatible insect trap.
